UNITED STATES PATENT OFFICE.

RALPH H. Langley, of Schenectady, New York, assignor to General Electric Company, a corporation of New York.

DESIGN FOR A RECEIVING LOOP.

Application filed December 12, 1925. Serial No. 15,731. Term of patent 14 years.

To all whom it may concern:

Be it known that I, RALPH H. Langley, a citizen of the United States, residing at Schenectady, in the county of Schenectady, State of New York, have invented a new, original, and ornamental Design for a Receiving Loop, of which the following is a specification, reference being had to the accompanying drawing, forming a part thereof.

The accompanying drawing is a perspective view of my new design.

I claim:

The ornamental design for a receiving loop, as shown.

In witness whereof, I have hereunto set my hand this 11th day of December, 1925.

RALPH H. Langley.
